DESIGN FOR A MEAT-TENDERING DEVICE

Vytant Aleks, Rockford, Ill., assignor to Ebaloy,
Incorporated, Rockford, Ill., a corporation of Illinois

Application December 29, 1945, Serial No. 125,141

Term of patent 14 years

(Cl. D89—1)

To all whom it may concern:

Be it known that I, Vytant Aleks, a citizen of the United States, residing at Rockford, in the county of Winnebago and State of Illinois, have invented a new, original, and ornamental Design for a Meat-Tendering Device, of which the following is a specification, reference being had to the accompanying drawings, forming a part thereof.

In the drawings:

Fig. 2 is a rear elevational view.

Fig. 3 is a front elevational view.

Fig. 4 is a plan view.

Fig. 5 is a side elevational view.

Fig. 6 is a section taken along the line 6—6 of Fig. 5.

I claim:

The ornamental design for a meat-tendering device, substantially as shown.

VYTANT ALEKS.
